(57) **CLAIM**

The ornamental design for a ball joint, as shown and described.

DESCRIPTION

FIG. 1 is a perspective view of my new design; FIG. 2 is another perspective view thereof; FIG. 3 is a side elevational view thereof, the opposite side being a mirror image; FIG. 4 is another side elevational view thereof, the opposite side being a mirror image; FIG. 5 is a top plan view thereof; and, FIG. 6 is a bottom plan view thereof. The broken lines showing of FIGS. 1–6 are for illustrative purposes only and therefore establish no part of the claimed design.
